GAME BOARD

Filed May 20, 1922

FIG. 1.

FIG. 2.

Inventor:
George E. Brown
Thomas J. Dennelly
Attorney

UNITED STATES PATENT OFFICE.

GEORGE EDWARD BROWN, OF LOS ANGELES, CALIFORNIA.

GAME BOARD.

Application filed May 20, 1922. Serial No. 562,492.

My invention relates to improvements in games and more particularly to a game board hereinafter disclosed as the specifications proceed.

5 The object of this invention is to provide a game which requires considerable skill to be played and adapted to be played by a number of players.

10 Another object is to provide a game similar to that of horse shoe, that may be played in doors.

A further object is to provide a game board, with suitable racks for the game pieces, when not in use by the players.

15 Also, another object is to provide the game board with suitable racks for the counting chips used therewith.

Other objects that might be mentioned, is that of having an irregular figure about the 20 stakes, that the game pieces resting thereon, will afford additional counts to the players.

The invention resides in the combination and arrangements of parts and in the details of construction hereinafter described and 25 claimed, it being understood that changes in the precise embodiment of the invention here disclosed can be made, within the scope of what is claimed without departing from the spirit of the invention.

30 In reference to the accompanying drawing Fig. 1, represents a plan view of the game board; Fig. 2 is a longitudinal section taken on the line 2—2 of Fig. 1; Fig. 3 is a plan view on one of the game pieces; Fig. 4 is the side elevation of a game piece; Fig. 5 is a vertical section taken on the line 5—5 of Fig. 1, showing the chips or counter rack; Fig. 6 is a vertical section, showing the end elevation of the game piece rack.

40 In the embodiment illustrated a board 1 is shown which may be of any suitable or desired material, having a vertical flange around the edge thereof. The board 1, is shown provided with the stakes 3, protruding vertically above the plane of the board and secured thereto, although the game may be played and enjoyed with but one such stake as herein shown.

The game pieces 4, as shown in Figs. 3 and 50 4 are to be placed back of the pitching line 5, that is farthest from the objective stake 3.

I prefer to snap the pieces 4 with the finger; however, they may be thrown or tossed toward the stake 3. The object being to encircle the stake 3 to gain the highest 55 count. However if after a number of players have snapped or tossed their respective game pieces 4, none have encircled the stake, the one closest thereto is given the highest counts. For additional interest I 60 have provided an irregular figure 6, representing a lariat, about the stake 3, and any game piece resting thereon is given a small count. For a purpose of clarity, I might state that a game piece encircling 65 the stake counts five, while pieces resting nearest the stake counts three, and a piece resting upon the irregular Figure 6 would count the player one. After the play has been made each player is allowed to take 70 from the rack 7, the chips 8, corresponding to the number of points made by the respective players. The chips 8, may be colored differently in each compartment 12, to assist the players in counting the game. I have 75 preferred to show the chips 8, in the following colors, red, blue and green.

In Figure 1, I show the rack 9 for the game pieces. In Fig. 6 you will note undercut 10 of the rack 9 permitting the game 80 pieces to be passed on from the end. It is apparent that while the game pieces are so reposed, if by accident the board should be overturned the pieces would remain on the rack. Fig. 2 shows the game pieces 4 in 85 their normal positions.

From the above description, it will be obvious that a game board constructed as described will amuse the players.

Thus having described my invention, 90 what is new and novel and what I desire to secure by Letters Patent is:

1. In combination with a game board adapted for use with separable game pieces, a rack mounted on and projecting upwardly 95 from said board, said rack comprising a base, a constricted portion projecting upwardly from said base; and a head mounted on said constricted portion, said head being provided with a plurality of transversely extending notches formed therein.

2. In combination with a game board

adapted for use with separable substantially U-shaped game pieces, an elongated rack mounted on said board and comprising a base; a neck projecting upwardly from said base to provide a constricted portion; and a head mounted on said neck, provided with a plurality of transversely extending notches on the upper surface thereof, adapted for

the reception of said game pieces when not in use.

10

In testimony whereof, I have hereunto signed the foregoing specification, at Detroit, county of Wayne, and State of Michigan.

GEORGE EDWARD BROWN.
